UNITED STATES PATENT OFFICE

FRANK MACMILLAN, OF FORT LEE, NEW JERSEY

ICE SKATE

Application filed December 22, 1931. Serial No. 582,526.

This invention relates to ice-skates, its principal object being to provide a skate having an inherently resilient runner so constructed and mounted in relation to the body 5 of the skate that when lateral pressure is exerted on the runner by the skater during the execution of a curve the runner is temporarily bowed or bent in conformity with the curve and is brought into extended contact with the 10 ice; thus enabling the curve to be taken at high speed with facility.

Another object of the invention is to provide such a skate wherein the resilient runner presents an extended engaging surface 15 to the ice during straight-ahead skating.

A further object of the invention is to provide in such a skate means whereby the runner can be readily attached to or detached from the body of the skate, as desired.

With these and other objects in view my 20 invention comprises features of novelty which will be hereinafter described; the scope of the invention then being defined in the appended claims.

In the drawings—

Figure 1 is a side elevation of a skate embodying the principle of my invention.

Fig. 2 is a bottom view of the skate, showing the runner as bowed or flexed from end 30 to end.

Figs. 3 and 4 are transverse horizontal sections through the respective ends of the body bar, as on the lines 3—3 and 4—4 of Fig. 1.

Fig. 5 is a transverse vertical section 35 through the pivotal connection at the forward portion of the runner, as on the line 5—5 of Fig. 1.

Fig. 6 is a section similar to Fig. 4 of the forward end of the body bar showing a slight 40 modification of the pivot retaining slot in the bar.

Fig. 7 is a side elevation, partly in section, of the body bar and runner of a skate embodying a modified form of pivotal connection 45 for the runner.

Fig. 8 is a transverse vertical section, as on the line 8—8 of Fig. 7.

The skate body or shoe-support illustrated in the drawings embodies a bar 10, preferably 50 a metal tube of rectangular cross-section, and

spaced sole and heel plates 11, 12, respectively, which are supported above the bar by suitable posts 13 rising from the bar.

A relatively thin blade or runner 14 composed of inherently elastic metal, as spring 55 steel, having its upper edge stiffened throughout its length by an additional thickness of metal 15, is arranged under and longitudinally of the bar 10 and has vertical pivotal connections with the latter at points forwardly 60 and rearwardly of the adjacent supporting posts. In the present instance one of the connections is located rearwardly of the heel plate and the other connection under the sole plate. 65

The bottom of the runner 14 is slightly downwardly curved or inclined from its extremities toward its mid-portion to afford a longitudinally convex ice-engaging surface, and hence when lateral pressure is exerted by 70 the skater upon the slanted runner during the execution of a curve, the runner, by virtue of its resiliency and its spaced pivotal connections to the body bar, is bowed or bent throughout its length in conformity with 75 the curve, as indicated in Fig. 2, and the bottom of the runner is brought into extended contact with the ice, thus enabling the curve to be taken at high speed with facility.

When the curve is completed and the skate is raised 80 from the ice the runner automatically resumes its normal or straight position. Since the runner is supported adjacent its ends the lower intermediate portion thereof is slightly sprung laterally by the weight of the skater 85 during straight-ahead skating, thereby presenting an extended engaging surface to the ice. The stiffening or reinforcing of the top of the blade more uniformly distributes the weight and pressure of the skater between the pivot connections and prevents undue flexing of the thin acting portion of the blade and the raising of its midportion from the ice. 90

In the present instance the pivotal connections between the runner and the bar 10 95 include knees 16 fast on the reinforced portion of the runner and having up-standing studs 17 provided with oblong or laterally-reduced head portions 18.

The bottom of the tubular body bar has 100

formed therein adjacent its respective ends corresponding **T**-slots 19, into the cross-portions of which the heads 18 of the respective studs 17 of the runner, when the latter is manually positioned below and parallel with the bar, can be freely entered and the runner then moved endwise relatively to the bar to position the studs in the longitudinal portions of the respective slots, thus pivotally interlocking the respective studs with the body bar. Suitable means to lock the pivots in the longitudinal portions of the slots 19 is provided, which means, in a simple form thereof, comprises a cross-bolt 20 extending through orifices in the sides of the bar in close relation to the head of the forward stud 17, as seen in Fig. 3. Thus the dual pivotal connection between the runner and the body bar is effectually maintained and at the same time the runner has capacity for slight movement of the rearward pivot toward and from the other pivot to accommodate the flexure of the runner. By removing the cross-bolt 20 from the body bar the runner can be readily detached for convenience of repair or replacement.

The slot at the forward end of the body bar may be a straight slot extending longitudinally of the bar, as shown at 190 in Fig. 6, in which case the pivots are entered in the slots at the respective ends of the bar as follows: The runner being positioned at a right angle to the bar and with the head 18 of the forward stud adjacent and parallel with the slot 190, such head is freely entered in the slot and the runner bodily swung to a position longitudinally of the bar to cause the inserted head to overlie the slot and the head of the rear stud to be located at the cross-portion of the adjacent **T**-slot 19 and entered therein. This done the runner is slid longitudinally of the body bar to engage the head of the rear stud with the leg of the **T**-slot, thus interlocking the respective ends of the runner with the bar.

In the modification shown in Figs. 7 and 8 the pivot studs 17 are prolonged and loosely fitted in vertical holes in the top and bottom of the bar 10, the upper ends of the studs projecting above the bar and being threaded to receive retaining nuts 21. By removing the nuts from the studs the runner can be released and detached from the body bar.

It is to be understood that my invention is not limited to the particular construction herein disclosed as the same may be modified within the principle of the invention and the scope of the appended claims.

I claim—

1. An ice-skate comprising a body including a shoe-support, a resilient runner having a longitudinally convex ice-engaging surface, and means providing vertical pivot con-

nnections between said runner and the body at points adjacent the respective ends of the runner.

2. An ice-skate comprising a body including a shoe-support, a resilient runner having a longitudinally convex ice-engaging surface and reinforced along its upper edge, and means providing vertical pivot connections between said runner and the body at points adjacent the respective ends of the runner. 70

3. An ice-skate comprising a bar, sole and heel plates and supports between said plates and the respective end portions of the bar, a resilient runner having a longitudinally convex ice-engaging surface, and vertical studs fixed to said runner and pivotally mounted in the bar at points forwardly and rearwardly of the respective supports. 80

4. An ice-skate comprising a body including sole and heel plates, a resilient runner detachably mounted on said body and having a longitudinally convex ice-engaging surface, and means providing vertical pivot connections between said runner and body, one of said connections located under the sole plate and the other connection rearwardly of the heel plate. 85

5. An ice-skate comprising a body including sole and heel portions, a resilient runner having a longitudinally convex ice-engaging surface and a reinforced upper edge, vertical studs fixed to said runner and pivotally mounted in said body at points adjacent the respective ends of the runner, and means for detachably securing said studs to the said body. 95

6. In an ice-skate, a body bar having slots adjacent its respective ends, a resilient runner, vertical studs fixed on said runner in spaced relation and having head portions to be entered in the respective slots and slid into interlocking engagement therewith by a longitudinal movement of the runner, and means for maintaining said heads in locked position. 100

7. In an ice-skate, a body bar having locking slots adjacent its respective ends, one of said slots being straight and the other **T**-shaped, a runner, vertical studs fixed on said runner and having **T**-heads for engagement with the slots, one of said heads being adapted to enter the straight slot when the runner is at an angle to the bar and the other head being adapted to enter the cross-portion of the **T**-slot when the runner is swung to a position longitudinally of the bar, so that the runner can be slid longitudinally to effect the interlocking engagement of the heads with the respective slotted portions of the bar, and locking means for the head at the end of the bar adjacent the straight slot. 115

8. An ice-skate comprising a body including a shoe-support, a resilient runner having a longitudinally convex ice-engaging surface, 120

and spaced vertical pivot connections between the runner and body, adjacent each end of the runner, one of the pivots being free to move towards the other pivot when the runner is
5 curved.

Signed at New York, in the county of New York and State of New York, this 21st day of December, A. D. 1931.
